UNITED STATES PATENT OFFICE.

ANDREW J. ASCH, OF NEW YORK, N. Y.

BACKING FOR ARTIFICIAL TEETH.

1,140,936.

Specification of Letters Patent. Patented May 25, 1915.

Application filed March 10, 1915. Serial No. 13,388.

To all whom it may concern:

Be it known that I, ANDREW J. ASCH, a citizen of the United States, and a resident of the city of New York, borough of Manhattan, in the county and State of New York, have invented a new and Improved Backing for Artificial Teeth, of which the following is a full, clear, and exact description.

This invention relates to bridge, crown and plate work in dentistry and has to deal more particularly with a backing for the facing of a tooth.

The invention has for its general objects to provide a novel, simple and effective means for interchangeably and replaceably mounting the facing of a tooth on a base or body of the bridge, crown or plate by the use of a backing so designed that it will be permanently secured in place, and to which the facing of the tooth is fastened.

A further object of the invention is the provision of a novel form of backing especially designed for use in connection with artificial porcelain teeth, known as facings, of that type having two rearwardly extending spaced pins, and the backing is provided with a pair of sockets into which the pins extend and are each securely fastened by a soft cement so that in case of the facing breaking off, due to wear or any other cause, it is merely necessary to pull out the pins that remain in the backing and apply a substitute facing, the advantage being that it is unnecessary to remove the bridge if the same be of the permanent kind, and also being that the invention makes use of a tooth facing which is of standard form and a staple article of the trade. Of course the backing can be made with a single socket for use with a facing having only a single pin, but in this case the socket and pin will be of non-circular cross-section to assist in preventing the facing from pivoting on the pin.

According to common practice, the backings used are provided with openings which receive the pins on the facing, and these pins are bent back against the back face of the backing. Thus, when the body of the crown, bridge or plate is soldered to the backing, the pins are soldered also, so that the pins cannot be pulled out, if the facing breaks off, as they can with this invention. For this reason the repair work, according to the old practice, is tedious, expensive and difficult.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views, Figure 1 is a front view of a bridge with two teeth completed, and a backing ready to receive facings; Fig. 2 is a sectional view on the line 2—2, Fig. 1; Fig. 3 is a perspective view of a portion of the bridge with a backing applied; Fig. 4 is a rear perspective view of a tooth facing; Fig. 5 is a rear perspective view of a backing or tooth facing; and Fig. 6 is a perspective view showing a facing and backing of the single pin type.

In the present instance the invention is shown in connection with bridgework, but it is not necessarily limited to this application.

Referring to the drawing, A designates the body of a bridge which is provided with the usual securing pins 1, and carried by the bridge body A are the artificial teeth B in the form of porcelain facings which are of usual construction and embody two parallel and spaced rearwardly extending pins 2 suitably embedded in the tooth facings. Each facing is provided with a backing C which is a plate of metal or equivalent material shaped to fit the rear surface of the facing, and this plate or backing C has a pair of spaced parallel sockets 3 which perform the double function of forming means for attaching the backing to the body of the bridge and for receiving and holding the pins 2 of the tooth facing. These sockets are shown as cylindrical and having their back portions closed. The body of the bridge is made in the usual manner. The pins 2 of the facing are anchored in the sockets 3 by means of soft cement 4 which serves to rigidly secure the facing to the backing. When, however, the facing breaks off by being worn, the backing remains *in situ*, and it is merely necessary to pull out the pins 2, and after scraping out any adhering cement from the sockets 3, a new tooth face is applied, using soft cement as a means for anchoring the pins of the new

tooth facing in the sockets 3. It will thus be seen that the tooth facings can be easily, quickly and inexpensively replaced without the necessity of removing the bridge or 5 crown body. The invention does not necessitate the manufacture of a new form of tooth facing and the backing is a new article of manufacture of itself, and will be sold in connection with the present form of tooth 10 facings.

When a single pin type of tooth is used, the backing C', Fig. 6, has a non-circular socket 3' to receive a correspondingly shaped pin 2' on the facing B', so that 15 rotative strain on the tooth will be resisted.

From the foregoing description taken in connection with the accompanying drawing, the advantages of the construction and method of operation will be readily understood by those skilled in the art to which 20 the invention appertains, and while I have described the principle of operation, together with the device which I now consider to be the best embodiment thereof, I desire 25 to have it understood that the device shown is merely illustrative and that such changes

may be made when desired as fall within the scope of the appended claims.

Having thus described my invention, I claim as new and desire to secure by Letters 30 Patent:

1. A backing for a tooth facing, comprising a plate having integrally connected therewith a rearwardly extending pin-receiving socket and forming means for attaching the backing to a bridge, crown or plate body. 35

2. A backing for a tooth facing, comprising a plate adapted to fit the back of a facing and having a plurality of sockets integrally connected therewith and extending from the rear face of the backing, and the front ends of the sockets being open and the rear ends closed, and the sockets being 40 spaced apart. 45

In testimony whereof I have signed my name to this specification in the presence of two subscribing witnesses.

ANDREW J. ASCH.
